FOLDING TABLE LEG AND LATCH BRACKET
STRUCTURE

Charles O. Larson, Sterling, Ill.

Application April 13, 1951, Serial No. 220,879

3 Claims. (Cl. 311—99)

1

This invention relates to brackets or hinge structures for pivotally and foldably mounting legs to the under surfaces of a table or support having a planar surface.

It is an object of the present invention to provide a novel bracket or hinge construction, whereby legs may be foldably secured to a table top so that they may be swung from an open vertical position to a folded position parallel with the table top and will be held in either of said positions by engagement of the leg with the table top and/or a wall of the bracket without need for any additional fastening means.

Another object of the present invention is to provide in a table construction a simple device for foldably mounting legs to the table top which device includes a slotted socket member secured to the table and a pin extending from the legs with said slot being so constructed and the pin being so positioned that the leg may be swung from an open vertical position with its top edge abutting the lower surface of the table to a folded position with an elongated side of the leg parallel with the table top and with at least the top portion thereof engaging the table top whereby the leg is locked in either of said positions without the aid of any other holding means.

Still another object of the present invention is to provide a novel device for foldably mounting legs to a table top, which device includes a socket member having opposed sides and an end wall, said opposed sides having aligned slots with angularly disposed portions and a pin extending from the legs and into the slots, with the slots being so constructed and the pin being so positioned that the leg may be swung from an open vertical position with its top edge abutting the lower surface of a table top to a folded position with an elongated side of the leg parallel with and abutting the table top and an upper end of the leg abutting the end wall of the bracket, whereby the leg is prevented from swinging or pivoting from either of said positions without need for any other holding means.

Another object of the invention resides in providing the cross pin carried by the leg with clamping means whereby if desired to provide additional means for holding the leg either in extended position at right angles to the table top for supporting the table in open position or wherein the leg or legs may be held in folded position parallel to and adjacent the under side of the table.

These and other objects of the invention will be apparent on perusal of the following specifica-

2

tion when taken in connection with the accompanying drawings wherein:

Fig. 1 is a perspective view of the invention as applied to a folding leg table showing the leg in open position;

Fig. 2 is a section on line 2—2 of Fig. 1;

Fig. 3 is a perspective view of the two plates forming the leg socket for the table;

Fig. 4 is a side view showing the leg in folded position with its side against the under side of the table;

Fig. 5 is a similar view showing the leg moved downwardly away from the table preparatory to swinging at an angle of 90 degrees to open position;

Fig. 6 is a successive view showing the leg swung to a 90 degree open position;

Fig. 7 is still another successive view showing the leg moved upwardly with the upper surface 20 of the leg abutting or substantially abutting the under side of the table; and

Figs. 8 and 9 are successive views of a modification of the invention.

Referring now to the invention in general, the invention herein comprises preferably, but not exclusively, a socket member which may be attached to the under side of a table top 2, or in fact any other top, and at the corner thereof as shown in Fig. 1. There are four of these socket members for the four corners of the table. As shown in detail in Fig. 3, the socket is preferably formed of two plate-like sheets of metal or other desired material, and comprises a flat plate-like member 4 having a right angled extending flange 6 at one edge thereof and a separate flange 8 extending at right angles to the plane of the plate 4 but along a different side or along a side that is at right angles to the flange 6. The opposite plate 10 is similarly provided with a flange 12 corresponding to the flange 6 and a flange 14 corresponding to the flange 8. The flanges 6 and 12 are provided with nail or screw holes 16 and 18 and 20 and 22 whereby these plate-like halves when in assembled position as shown in Fig. 1

45 with the edges 24 and 25 of the flanges 6 and 14 in juxtaposition as shown in Fig. 1, there will be formed a socket member into which the upper end of a leg 26 may be inserted. In Fig. 1 screws 28 are shown passing through the holes 16, 18, 20 and 22 for attaching the plates 4 and 10 in assembled relation to the under side of the table top 2.

The two side plates 4 and 10 of the leg socket member provide a rectangular socket for the leg 26 which is of rectangular conformation and fits

snugly within said socket. As shown in Fig. 2, in the open position of the leg, its upper surface 30 is adapted to contact preferably the under side of the table top 2 thereby providing a rigid support.

Means is provided forming a foldable connection between the socket member and the leg, and this comprises a cross pin 31 preferably having a head 32 and a threaded shank 34 adapted to receive a threaded wing nut 36. The pin 31 passes through a round hole formed in the upper portion of the leg 26 at a predetermined point thereof selected to accomplish the objects hereinafter described.

The opposed plates 4 and 18 constituting the socket in Figs. 1 to 7 inclusive are provided with registering slots, each slot comprising a relatively shorter portion 40 merging into and joining with an angularly disposed portion 42. The opposite plate is likewise provided with a similarly shaped and arranged slot. In Figs. 1 to 7 the shorter upper portion 40 of the slot is disposed vertically with respect to the socket plates 4 and 18, whereas the branch portion of the slot 42 is disposed at an acute angle thereto and, as shown in Fig. 1, branches to the right. The lower branch 42 is longer than the branch 40 and the arrangement is such with respect to the length of the branches 40 and 42 so that when the cross pin which slides in these joined together slots of the two plates 4 and 18 slides in the upper portion 40 of the slot, it will contact the end 43 of such upper portions as shown in Fig. 4. In this position the table leg 26 will have been folded into parallelism with the under side of the table 2 and substantially abutting or abutting the same. In this position it is readily seen that the leg 26 will be locked in position since if the leg 26 tends to pivot about the pin 31, it will be restrained by the engagement of the top portion of the elongated side of the leg 26 with the under surface of the table top and/or by the engagement of the upper surface or edge 30 of the leg 26 with the flanges 8 and 14 of the plates 4 and 18. Now, in this position by pulling down upon the table leg 26, the pin will ride downwardly along the slot 40 and will thence ride along the angularly disposed portion of the slot 42 until it comes to the end 44 of said portion. In this position the leg 26 will be shifted away from the under side of the table 2 in the position shown in Fig. 5. In this position the leg 26 may now be shifted exactly at right angles into the position shown in Fig. 6. Thereafter the leg is then moved upwardly, the pin riding along the long slot portion 42 and thence into the shorter slot portion 40 until the pin 31 strikes the upper end 43 of the slot 40. This corresponds to a position such that the upper edge 30 of the leg contacts or substantially flushly contacts the under side of the table. Due to the angular disposition of the upper edge of the leg to the under side of the table and the arrangement of the socket members enclosing three sides of the leg, the leg will be held in open position. This applies to all four of the legs, and each leg is shifted in the above described manner in turn until the table is either in folded position or unfolded position with all four legs extending at right angles to the table top. In this position, if desired, the wing nut 36 may be tightened whereby to prevent any inadvertent downward movement of the table top should any wear occur in the slot member.

It is to be understood that in either position the wing nut may be tightened to hold the leg 75

either in extended right angular position with respect to the table top or in folded adjacent position with respect to the table top.

In Figs. 8 and 9 the invention is shown with modified slots wherein the shorter branch 46 of the slot lies parallel to the under side of the table top, the longer branch 48 of the slot occupying the same angular position as did the slot portion 42 in Figs. 4 to 7 inclusive. This modification of the invention is otherwise similar to the form shown in Figs. 1 to 7 inclusive, and operates in the same manner generally speaking.

The sleeve or bracket may be formed of one single piece of material if desired instead of forming the same of separable halves.

Having thus described my invention, what I claim as new and desire to secure by Letters Patent is:

1. In combination, a bracket having a pair of spaced apart vertically disposed side plates having upper horizontal edges and vertically disposed end edges, means providing an end wall between adjacent vertical edges of said side plates for closing one end of the bracket with the opposite end of the bracket being completely open, a pair of flanges extending substantially horizontally outwardly from said upper edges of the side plates for mounting the bracket to the under surface of a support, such as a table top, said flanges having upper surfaces disposed in a common plane, a leg having a substantially flat upper end and having an upper end portion disposed between said side plates, said side plates having registering elongated slots of uniform width therein, which slots have an upper portion disposed generally parallel with an edge of the side plates and a connecting lower portion disposed at an angle to said first mentioned portion and inclined downwardly and toward said open side of the bracket, said first mentioned portions of the slots terminating with one edge spaced a predetermined distance from said common plane and a second edge spaced from said end wall a distance substantially equal to said predetermined distance, a pin having a diameter substantially equal to said uniform width of the slots, said pin extending through the upper portion of said leg with end portions of the pin slidably disposed in the slots, said pin being located in said leg so that the pin is disposed distances substantially equal to said predetermined distance from the upper substantially flat end and opposite longitudinal side edges of the leg so that said leg may be disposed in an open vertical position with said substantially flat upper end in said common plane and one of said longitudinal side edges abutting said end wall, and said leg being movable to a folded position with said substantially flat end of the leg in engagement with said end wall, and the other of said longitudinal edges of the leg having a portion between said substantially flat end and the pin disposed in said common plane for locking the leg in the folded position.

2. A combination, as defined in claim 1, wherein in said first mentioned portions of said slots are disposed substantially parallel to the vertical edges of said side plates.
